UNITED STATES PATENT OFFICE

JACOB CLEMMONS YOUNG, OF BEAUMONT, TEXAS, ASSIGNOR OF THIRTY-FIVE ONE-HUNDREDTHS TO EDWARD TAYLOR MILLER, OF BEAUMONT, TEXAS

ROPE DISPLAY STAND

Application filed May 5, 1928, Serial No. 275,400. Renewed January 29, 1931.

This invention relates to display racks for exhibiting goods and holding the same in convenient position for dispensing as required.

5 The invention provides a stand including a base, an upright, reels, guides, and holders. Each of the reels comprises a spindle, retainers, centers and a holder, the latter preventing displacement of the parts when assembled.

10 While the drawings illustrate a preferred embodiment of the invention it is to be understood that in adapting the means to meet specific needs and requirements the design 15 may be varied and such other changes in the minor details of construction may be resorted to within the scope of the invention as claimed, without departing from the spirit thereof.

20 For a full understanding of the invention and the merits thereof, reference is to be had to the following description and the drawings thereto attached, in which:—

Figure 1 is an elevational view of a display stand embodying the invention.

Figure 2 is a top plan view of the base, the upright being in section on the line 2—2 of Fig. 1.

Figure 3 is a detail perspective view of a 30 portion of the upright and one of the reels and guides applied thereto, showing a coil of rope in position.

Figure 4 is a detail view, the parts at the outer end of the spindle being detached.

35 Figure 5 is a detail view of the top portion of the upright, the top guide, and a portion of the top reel.

Figure 6 is an enlarged fragmentary sectional view of the outer portion of a reel.

40 Corresponding and like parts are referred to in the following description and designated in the several views of the drawings by like reference characters.

The stand or display rack embodies a base 45 1, and an upright 2 projecting vertically from the base and secured thereto by angle irons 3. The base 1 may be of any preferred construction, size and shape, and is mounted upon casters 1a for convenience of moving 50 the rack as occasion may require. The up-

right 2 usually consists of a post of any determinate length according to the number of reels to be supported. The reels are of like structure and are disposed at the sides and top of the upright, and a guide is associated with each of the reels to receive the loose end of the rope, as indicated most clearly in Figure 3 of the drawings.

55 Each of the reels includes a spindle 4, retainers 6, and centers 7, the latter being of conical form, and expandable to readily conform to the different sizes of openings in the various coils of rope to be displayed. The spindle 4 preferably consists of metal pipe which is secured in openings bored in the upright 2. In the preferable construction the reels progressively decrease in size from the base 1 towards the top of the upright 2, as indicated most clearly in Figure 1 of the drawings.

60 Opposite reels have spindles in common. A length of pipe is passed through a transverse opening formed in the upright 2 and adjusted so that each end projects from the upright a like distance. A pin 9 is passed 65 through the upright and pipe and secures the latter in the required adjusted position. The spindle 4a of the top reel is secured in an axial opening bored in the top of the upright 2. Two retainers and two centers are 70 provided for each of the spindles, and are located at opposite ends thereof. Each of the retainers includes a hub and radial arms which are designated by the numeral 6.

75 The hub includes two plates 10 and 11 between which the inner ends of the arms 6 are clamped, each of the plates being pressed outwardly to receive the arms 6 therebetween, the portions of the plates between the arms being in contact and riveted or otherwise secured. A boss 12 projects from one of the plates to provide for an extended bearing upon the spindle. The centers 7 are 80 hollow and receive the bosses 12. Each of the centers 7 is formed with an inwardly disposed boss 13 at the smaller ends to insure ample bearing upon the spindle. The center 7 is struck from sheet metal, and is 85 longitudinally split as at 13' to form resilient portions which may be contracted to ad- 90

mit of the center conforming to the size of the opening formed in the coil of rope 14. Various coils of rope have openings differing in size, hence the advantage of having the centers 7 constructed to adapt themselves to the various sizes of openings.

5 A holder is associated with each of the spindles to prevent displacement of the goods mounted thereon. Each of the holders 10 consists of a top 8 which is of a size to slip over the outer end of the spindle and a spring clip 8a which is pressed into the outer end of the spindle and engages the same frictionally to retain the holder against casual 15 displacement.

The guide includes an eye 5 and a rod 5a, the latter being of a length to project from opposite sides of the upright to provide a 20 guide for opposite reels. The rod 5a may be secured to a side of the upright in any determinate way. The guides progressively decrease in length from the base towards the top of the upright to conform to the decrease in the size of the reels. The top guide 25 is vertically disposed and the rod from which it is formed is offset, as indicated most clearly in Figure 5, the upper portion terminating in the eye being offset a distance to clear the bottom retainer of the top 30 reel.

While the rack is designed more particularly for displaying coils of rope, nevertheless it may be utilized for displaying goods in the form of rolls or coils. The opposite 35 disposition of the reels insures an equalization of the weight, and by having the reels decrease in size from bottom to top the rack is prevented from toppling over provided the goods are distributed so as to keep the 40 weight as near the base as possible.

Having thus described the invention, I claim:

1. A display rack comprising a base, an upright rising therefrom, and reels at the 45 sides of the upright and progressively decreasing in size from bottom to top of the upright, and guides associated with the reels and similarly decreasing in size from the base towards the top of the upright.

2. A display rack comprising an upright, oppositely disposed reels at the sides of the upright, and a rod secured to the upright and having end portions projecting beyond opposite sides thereof and terminating in 55 eyes to provide guides for cooperation with the reels.

3. A rack including a spindle, article supporting means thereon and a holder consisting of a top and a spring clip fixed thereto, the latter frictionally engaging the inner 60 walls of the spindle, and the top slipping loosely thereover and abutting the supporting means.

4. In a rack, a spindle, retainers at opposite ends of the spindle and having inward-

ly disposed bosses and expandible centers of conical form mounted upon the spindles and receiving the bosses of the retainers, said centers having inwardly disposed bosses at their smaller ends to obtain an extended bearing upon the spindle and abutting the first named bosses.

5. A display stand comprising, a base, mounted upon casters, an upright rising from the base, reels at the top and sides of the upright and gradually decreasing in size from the base upwardly, each of the reels including a spindle, retainers and self-expandible centers, and guides for the respective reels, each consisting of a rod terminating in an eye.

In testimony whereof I affix my signature.

JACOB CLEMMONS YOUNG.
